UNITED STATES PATENT OFFICE.

LUCIUS ANTON SMITH, OF BUFFALO, NEW YORK.

TRUSS.

1,294,963.

Specification of Letters Patent. Patented Feb. 18, 1919.

Application filed March 4, 1918. Serial No. 220,177.

To all whom it may concern:

Be it known that I, LUCIUS ANTON SMITH, a citizen of the United States, residing at Buffalo, in the county of Erie and State of New York, have invented new and useful Improvements in Trusses, of which the following is a specification.

My present invention pertains to trusses; and it has for its general object to provide 10 a comfortable and efficient truss, and one well adapted to withstand the usage to which trusses are ordinarily subjected and hence calculated to preserve its efficiency throughout the period of its use.

15 To the attainment of the foregoing the invention consists in the peculiar and advantageous pad, in the strap interposed between and connecting the depending arm of the spring and the pad, in the spreader for 20 maintaining the body straps in normal spaced relation with a view to retaining the truss comfortably in its proper working position, in the manner of connecting the leather to the spring, in the construction of 25 the spring, in the mode of effecting connection of said spring to the pad, and in the manner of connecting the pads of a double truss, all as hereinafter described and definitely pointed out in my appended claims.

30 In the accompanying drawings, which are hereby made a part hereof:

Figure 1 is a perspective of a truss for the right side constructed in accordance with my present invention.

35 Fig. 2 is an enlarged side elevation illustrative of some of the connections to the spring.

40 Figs. 3 and 4 are detail sections, taken in the planes indicated by the lines 3—3 and 4—4, respectively, of Fig. 2.

Fig. 5 is an enlarged elevation, showing the stretcher.

45 Figs. 6 and 7 are detail views of the pad and the connection of the spring thereto; Fig. 7 being taken in the plane indicated by the line 7—7 of Fig. 6.

Fig. 8 is a perspective showing my invention embodied in a double truss.

50 Fig. 9 is an enlarged front elevation of the strap employed to effect connection between the pads of the double truss to hold the said pads in proper spaced relation and to assist in maintaining the truss as a whole on the body.

55 Fig. 10 is a section taken in the plane indicated by the line 10—10 of Fig. 9.

Similar numerals of reference designate corresponding parts in all of the views of the drawings.

The truss shown in Figs. 1 to 7 is for the 60 right side, and its pad 1 is clearly shown in Figs. 1, 6 and 7. The said pad is formed of wood or other material compatible with its purpose; and it is peculiar and materially advantageous in that it has a lower 65 comparatively-thick and rounded portion 1^a, Fig. 7, at its side that is opposed to a patient's body, and is tapered from said portion 1^a, at said side, to its upper edge indicated by 2; the tapered surface being slightly 70 convex as clearly shown in Fig. 7. This pad does not round too suddenly and hence it does not stretch the skin over a suddenly rounded surface and cause soreness in such degree as to prompt a patient to discard the 75 truss as frequently happens when the pad is of ordinary configuration. On the other hand in the employment of my novel pad the pad assures the pressure on the skin gradually diminishing toward the top or 80 upper edge of the pad. It will also be observed that my novel pad rounds to a greater extent or more suddenly at 1^a adjacent to the leg, Fig. 7. Because of this the pad conforms to the anatomy as it lies next to 85 Poupart's ligament and at that point there is no such tendency to stretch the skin as there is on the other or inner side, and moreover such shape of the pad permits free movement of the leg without discomfort. 90

At 3 is the spring of my novel truss, though I would here have it understood that the said spring is not relied upon to afford the pressure necessary to hold the 95 rupture. It serves simply to hold the pad in position but in performing this function it exerts considerable pressure toward holding the hernia. As illustrated, the spring 3 comprises a curvilinear portion 4 which terminates at its forward end in a circular 100 portion 5, Figs. 6 and 7; the said circular portion 5 being interposed between the back of the pad 1 and a grooved metallic plate 6 that is connected to the pad through the medium of a screw 7, which screw also serves 105 to connect the strap 8, presently described, to the pad. At its end the circular portion of the spring is provided with an angularly-disposed stud 9 which is disposed in a socket 10 of the pad and hence in simple 110 manner and without the assistance of any extraneous element prevents turning of the

pad on the spring or the connecting screw. The upper end of the curvilinear spring portion 4 merges into a loop 11, and said loop 11 merges, in turn, into a depending arm 12 which in the spring for the right side is bent upon itself to form a loop 13 and is then carried downwardly and ends in a generally circular loop 14, Fig. 2.

The strap 8 described as connected at one end to the pad 1, is connected at its opposite end to the loop 13, and is designed to pass around the side of the hip of the wearer. This strap accommodates itself to the shape of the body between the depending arm 12 of the spring 3 and the pad 1 and exerts a pull counter to that exerted by the body straps from where said straps, which are numbered 15, are connected to the spring to where they are connected through the medium of an apertured tab 16 to a protuberance 17 on the pad. Said strap 8 also prevents the lower of the body straps from pulling the lower end of the depending arm 12 around too far toward the center of the back of the patient's body. From this it follows that it is feasible to have the spring light and flexible and consequently easy to wear; also, that all the pressure can be produced that a patient can bear, though the shape of the pad where it is designed to rest at the internal ring and on the inguinal canal is such that it holds with minimum pressure and is very comfortable.

As before stated the spring 3 is not relied upon to afford the pressure necessary to hold the rupture. On the other hand, the body straps 15 pulling over and exerting inward pressure on the pad edge 2—i. e., pressure toward the body of the patient, serve to materially support the pad and to press the same against the body of the patient.

At this point I would have it understood that my novel pad 1 may be used for a right side truss or for a left side truss; it being feasible to so use the pad as the socket 10, Fig. 7, is in the vertical center of the pad and opposite the pad portion 1^a.

20, Figs. 1 and 5, is a spreader designed 50 and adapted to maintain the body straps 15 in spaced relation where they pass around the hip opposite to the one upon which the spring 3 rests. The said spreader may be made of any material and in any manner provided it is sufficiently unyielding though I prefer to have it comprise a strip of webbing 21 designed to be arranged next to the body and a strip of resilient metal 22, together with loops 23 to receive the body 60 straps 15. The spreader may be fixed to or adjustable upon the body straps in the discretion of the manufacturer without affecting my invention; the type shown being adjustable by reason of its loops on the body 65 straps 15. The practical advantage of the

said spreader will be fully appreciated when it is stated that in order to hold a hernia with the least possible pressure it is necessary to place the lower strap 15 quite low where it passes around the back portion of the body or buttocks, and if the straps are not held apart as stated there is a tendency for the lower strap to creep upwardly with the result that its efficiency is seriously diminished.

75
In Figs. 1, 2 and 3 I clearly illustrate the leather covering 30 of the curvilinear portion of spring 3. The said covering comprises inner and outer thicknesses, the intermediate portions of which are disposed at 80 the inner side of the curved spring portion. At a point adjacent to the rear end of the leather covering an aperture 31 is provided through both thicknesses of leather, Figs. 1 and 3, while at 32 an aperture is provided 85 in the outer thickness of leather alone for the passage of the spring and the attachment of the forward end of the leather covering to the spring, the forward end of the inner thickness of leather resting at that 90 point between the spring and the body of the wearer with a view to promoting comfort. This will be understood by comparison of Figs. 1 and 2. The aperture 31 is for the passage of the upper body strap 15, 95 which is connected to a buckle 40, and it will be manifest that the said arrangement prevents the leather which forms a cushion under the buckle from being pulled out of place and turning under incidental to the 100 putting on of the truss, and at the same time the leather covering is enabled to steady the strap 15 and prevent it from shaking loose in the buckle. To connect the buckle 40 I cut the outer thickness of leather and turn it 105 back from the aperture 31, and secure it through the medium of a rivet 41, and by so doing I not only save leather in the fastening of the buckle but provide a covering having one less thickness than would be 110 the case were a separate piece of leather employed in the attachment of the buckle. It will be noted here that by disposing the two thicknesses of leather between the spring and the body except at the ends I provide 115 an adequate cushion between the spring and the hip of the wearer, and this with thin leather which tends to lessen the cost of the truss and conduces to the neat appearance of the same.

120
The leather covering 30^a employed at the lower end of the depending arm of the spring, Figs. 1, 2, 4 and 8, is generally similar in construction to the covering 30, and the buckle 40^a is connected with the covering 30^a in the same manner that the buckle 40 is connected with covering 30, while the lower body strap 15 is arranged in relation to the covering 30^a in the same manner that the upper strap 15 is arranged relative to 125 130

the upper covering 30 and its complementary buckle. At 32^a the covering 30^a has an aperture in its outer thickness for the passage of the spring.

5 By removing the body straps 15 and providing a left side truss such as shown in Fig. 8 in combination with the right side truss, and connecting the two trusses through the medium of back straps 15^a and 10 a front connection 50, Figs. 8 to 10, I provide a double truss of high efficiency. The said connection 50 is made up of an apertured strap member 51 for connection to the pad of the left side truss, and an apertured 15 member 52 for connection to the pad of the right side truss; the said member 52 comprising two thicknesses of leather and equipped with a buckle 40^b and having said buckle connected with the leather alone in 20 the same manner as the buckles 40 and 40^a, and being adapted to receive the strap member 51 in the same manner as described with reference to the connection of the body straps 15 to the spring 3 of the right side truss. It will be noticed by reference to 25 Fig. 9 that provision is made for convenient adjustment of the connection 50; also, that the leather 52 is comparatively wide to prevent the edges of the buckle contacting with the abdomen of the patient, and that with the connection 50 any desired adjustment may be obtained.

It will be noticed by reference to Fig. 8 that the spring 12^a at the left side of the 30 truss is provided with a "kink" 13^a in lieu of the loop 13 of spring 12. The loop 13 is superior to the "kink" 13^a in that it is adapted to more certainly hold the strap 8 against vertical shifting, as is essential, and 40 I would therefore have it understood that the left-side spring may be of the same construction as the spring 12, without affecting my invention.

Having described my invention, what I 45 claim and desire to secure by Letters Patent, is:

1. In a truss, the combination of a spring having a curvilinear arm and a depending arm on the rear portion of the curvilinear arm, a pad on the forward portion of the curvilinear arm, straps connected to the upper and lower portions of the depending arm, and a strap interposed between and connected to the pad and an intermediate portion of the depending arm of the spring.

50 2. In a truss, the combination of a spring

having a curvilinear arm and a depending arm on the rear portion of the curvilinear arm, a pad on the forward portion of the curvilinear arm, straps connected to the upper and lower portions of the depending arm, a stretcher interposed between said straps at an intermediate point, and a strap interposed between and connected to the pad and an intermediate portion of the depending arm of the spring.

55 3. In a truss, the combination of a spring terminating at its rear portion with a depending arm and at its front portion with a circular member secured to the rear face of a 60 pad, a leather covering comprising two thicknesses the outer of which receives the spring and both of which are apertured for the passage of a strap, and a buckle attached to the covering at the outside thereof.

70 4. In a truss, the combination of a spring, a leather covering comprising two thicknesses the outer of which alone receives the spring and both of which are apertured for the passage of a strap, and the outer of 75 which is cut from said aperture to form a loop which receives the spring and is attached to the major portion of the covering, and a buckle disposed at the outer side of the covering and held in the said loop 80 thereof.

85 5. In a truss, the combination of a spring having a curvilinear arm and a depending arm on the rear portion of the curvilinear arm, a pad on the forward portion of the 90 curvilinear arm, upper and lower straps connected to the rear portion of the spring, and a strap interposed between and connected to the pad and the arm of the spring.

95 6. In a truss, the combination of a spring having a curvilinear arm and a depending arm on the rear portion of the curvilinear arm, a pad on the forward portion of the curvilinear arm, upper and lower straps connected to the rear portion of the spring, 100 a strap interposed between and connected to the pad and the arm of the spring, and a stretcher interposed between and connected to the upper and lower straps.

105 In testimony whereof I have hereunto set my hand in presence of two subscribing witnesses.

LUCIUS ANTON SMITH.
